CLAIM

The ornamental design for a rectangular thermoplastic pile extrusion, as shown and described.

DESCRIPTION

FIG. 1 is a top plan view of a profile for an extruded thermoplastic pile.

FIG. 2 is a side view of the profile for an extruded thermoplastic pile shown in FIG. 1.

FIG. 3 is a first top perspective view of the profile for an extruded thermoplastic pile shown in FIG. 1.

FIG. 4 is a second top perspective view of the profile for an extruded thermoplastic pile shown in FIG. 1.

FIG. 5 is a third top perspective view of the profile for an extruded thermoplastic pile shown in FIG. 1; and,

FIG. 6 is a fourth top perspective view of the profile for an extruded thermoplastic pile shown in FIG. 1.

The rectangular thermoplastic pile extrusion is shown with a symbolic break in its length. The appearance of any portion of the rectangular thermoplastic pile extrusion between the jagged break lines forms no part of the claimed design. The broken lines in the drawings illustrate portions of a rectangular thermoplastic pile extrusion which form no part of the claimed design.
